AIR CONDITIONING APPARATUS

Edward S. Lea, Morrisville, Pa., assignor, by
mesne assignments, to George Von Seebeck,
New York, N. Y.

Application August 26, 1935, Serial No. 37,847

12 Claims. (Cl. 261—11)

My present invention considered from one aspect is concerned with an apparatus for conditioning air to heat and humidify in the winter time, to cool and dehumidify in the summer time, 5 to at all times insure thorough washing thereof and removal of odors and entrained solids and to permit optional humidification without heating or cooling, when such humidification is desired.

A feature of the invention is the division of the 10 air to be conditioned, into two streams, the thorough humidification and washing of one of these streams, with or without humidification of the other, and then the commingling of the streams and the heating of the body of air leaving the 15 conditioner apparatus. Where intensive dehumidification is required the flow of one air stream may be blocked and the other air stream intensely refrigerated and washed and subsequently supercooled.

20 Considered from another aspect the invention is concerned with an improved conditioning apparatus in the form of an all-purpose conditioning unit, suitable for large or small installations and of extremely compact construction, involving 25 a minimum number of parts likely to get out of order and requiring little or no attention in use and involving no complex control mechanism, and of simple, rugged, durable, inexpensive construction.

30 A feature of the invention is the use of a conditioning apparatus having a pair of air circulating fans, one of which is adapted to draw air through a humidifying and washing chamber and the other of which is adapted to draw air directly 35 from any suitable source and commingle it with the washed and humidified air.

35 Preferably the two fans are of the sirocco type having a common dividing plate between them and the air drawn by both fans is forced violent- 40 ly through a volute discharge chamber where excess moisture in the humidified stream is precipitated out and where thorough commingling of the two streams occurs. Refrigerating means may be employed in the humidifying chamber to cool 45 the wash water and selectively operable heating means may be employed at or beyond the outlet of the unit to heat the humidified stream of air for winter use.

Where refrigerating apparatus is used to cool 50 the wash water for purposes of dehumidification and cooling of the air in the summer time, I preferably pass part of the primary refrigerant leaving the wash water chamber, through a heat interchanger arranged in the outlet of the ma- 55 chine. This arrangement not only super-cools

the air leaving the machine but warms up the refrigerant to such an extent that the return refrigerant line of the compressor does not become frosted and the compressor may be disposed at any desired distance from the air conditioning unit proper without danger of constant drip of melting ice from the refrigerant return pipe.

The invention is likewise concerned with the provision of an extremely simple construction and arrangement of casing upon which the motor 10 is mounted within which the volute discharge passageway is enclosed, this casing having removably associated with the lower end thereof, a tank of wash water, preferably cooled by a refrigerant coil suspended from the casing it- 15 self so that the tank may be lowered and the refrigerating coil cleaned whenever such cleaning is desirable. Preferably a single vertically disposed shaft operated by the motor carries the two fans and the lower end of this shaft carries cen- 20 trifugal pumps or cone type slingers which create the necessary wash water spray in the region of the tank and which may likewise project smaller amounts of water into the fans themselves where the water becomes broken up to create a humid- 25 ifying mist. Adequate air inlets guarded by suitable filters are provided for the two streams of air, one of which travels directly to the upper fan and the other of which is drawn through the sprays and thence through the lower fan and 30 thrown with the substantially unconditioned stream into the volute outlet.

35 Power required for operating the unit is but slight and the conditioning of very substantial volumes of air per unit of time is efficiently accomplished. A feature of the machine is the particular arrangement of spray producing means and spray baffling means which insures flow of the air to be humidified or dehumidified sub- 40 stantially radially counter-current to the spray water and causes this air to traverse wet surfaces substantially from the time it enters the machine until it has nearly reached the exit of the volute outlet. In other words maximum intimacy of 45 contact between the spray water and the air is assured and maximum evaporative cooling effect is obtained.

The present invention represents very substantial refinements and improvements of structure 50 over the apparatus disclosed in my copending application Serial No. 755,916, filed December 4, 1934 (issued as U. S. Patent 2,079,574, on May 4, 1937).

The invention may be more fully understood 55

from the following description in connection with the accompanying drawings, wherein:

Fig. 1 is a vertical sectional view through an air conditioning apparatus embodying the invention,

Fig. 2 is a top plan view thereof,

Figs. 3, 4 and 5 are sectional plan views on the lines 3—3, 4—4 and 5—5 respectively of Fig. 1,

Fig. 6 is a view mainly in vertical section but 10 showing the slingers in elevation and illustrating the direction of travel and general action of the spray water and the water which forms the humidifying mist.

Fig. 7 is a sectional detail taken approximately 15 on the line 7—7 of Fig. 10,

Figs. 8 and 9 are sectional details taken approximately on the lines 8—8 and 9—9 of Fig. 1, and

Fig. 10 is a perspective view of an air conditioning unit constructed in accordance with the invention.

Referring with more particularity to the drawings, and particularly to Figs. 1 and 10 thereof, the reference numeral 12 indicates a supporting 25 frame for the casing of the machine, this frame being preferably formed of steel angle members and being closed at three sides, if desired, by sheet metal side plates 13. An approximately rectangular lower casing section 14 is supported 30 on horizontal bars 15 constituting part of the frame 12, the support means preferably comprising brackets 16 fixed to the casing section 14 and carrying rubber cushion feet 17 which rest upon the frame bars 15.

35 A window 18 in the casing section 14 permits visual observation of the action of the spray water. The lower end of the casing section 14 extends within an insulated tank 19 resting upon a secondary frame 20 located within the frame 12. Suspended within the tank from suitable brackets 21 carried by the casing section 14, is a refrigerating coil 22, this coil having an inlet header 23 and an outlet header 24. A suitable volatile refrigerant is adapted to be supplied from the condenser of a standard refrigerating system to the pipe coil 22 and I have illustratively shown a refrigerant line 25 adapted to deliver refrigerant from a condenser to the header 23. The refrigerating apparatus has been illustrated only diagrammatically by showing part of the compressor 26.

The lower casing section 14 in addition to carrying the weight of the refrigerating coil, preferably also mounts a water supply pipe 27 through 55 which water is supplied to the tank 19. Preferably the admission of water to the tank is controlled by a float valve 30 and water overflows from the tank through an overflow pipe 31. The generally rectangular sheet metal casing section 14 also sustains the weight of an upper casing section 32 likewise of generally rectangular shape and provided at its lower edge with a generally inverted V-shaped rim 33 which rests directly upon the top of the casing section 14. Casing section 32 is provided with a pair of air inlets 34 and 35 adjacent the upper end thereof, each of 60 these inlets being guarded by removable filters 36. Arranged adjacent the upper end of the casing section 32, is a horizontally disposed approximately doubly volute separator chamber 37, this chamber being defined by top plate 38a, bottom plate 38 and a spiral partition forming member 39, the latter being most clearly seen in Fig. 4. Mounted centrally of this chamber is a double 65 sirocco fan comprising an upper fan element

40 and a lower fan element 41, the two fans being separated by a common horizontal partition plate 42, and the entire double fan unit being secured by a hub 43 on a vertically disposed driving shaft 44, the latter mounted upon a thrust bearing 45, 5 arranged in the lower end of a hollow sleeve 46. This sleeve, which is adapted to be filled with lubricant, is pendant from a relatively massive plate 47 which covers an opening 48 in the top of the casing section 42 and rests at its edges on a 10 suitable cushioning gasket 49. Plate 47 near its periphery carries a block 50 in which an electric motor 51 is adjustably mounted, that is to say, the motor is adjustable on its block toward or away from the center of the plate. The drive 15 for the shaft 44 is through an endless flexible device 52 which connects a pulley 53 on the pendant motor shaft with a pulley 54 on the extended reduced upper end 55 of the shaft 44. To vary 20 the speed of the shaft 44, motor 51 may be adjusted inwardly or outwardly on its support block 50 and pulleys of different sizes substituted for the pulley 53.

Air entering the machine through the inlet 34 passes through a set of dampers 56, flows between the top of the casing section 32 and the top plate 38a of the volute conduit and is drawn downwardly into the upper fan 40 through a tapered inlet duct or channel 57. Air from the inlet 35 flows downwardly under the volute conduit 30 and after being subjected to a violent rain water spray as will be later described, is drawn upwardly into the lower fan 41 through an inverted, generally conical duct 58.

Arranged centrally of the tank 19 is a well 60, 35 the top of which is disposed above the normal water level in the tank. Water flows into the lower end of this well through a valve 61 controlled by a push rod 62.

As best seen in Fig. 9, the valve 61 constitutes 40 the flat surface of one end of a lever 63, fulcrumed intermediate its ends on a pin 64. The valve serves to close the opening 65 through which water is admitted to the well but preferably does not effect a tight seal, to the end that some 45 slight amount of water may always leak into the well for purposes which will be more fully hereinafter described. The push rod 62 engages that end of the lever remote from the valve end thereof and may be operated by any suitable 50 thermostatic or hygostatic regulating means illustrated diagrammatically at 66 in Fig. 1.

The shaft 44 carries two or more concentrically arranged cone type pumps or cylinders having their reduced open lower ends disposed below the normal water level in the well 60. The innermost slinger 67 is provided with an internal spider 68 carrying a hub 69 secured to the shaft 44. This slinger extends upwardly through the lower end of the fan section 41 and is preferably provided with a flange 70 welded or otherwise secured against the common partition plate 42 between the two fan sections.

Within the lower fan section 41 the slinger is 65 provided with a plurality of openings 71 through which water rising in the cone is projected laterally into the blades of the fan section 41 and thoroughly broken up by these blades to afford an atomized mist. Inasmuch as it is usually desirable to also humidify the air stream by the upper fan section 40, some of the water rising along the conical wall of the slinger 68 escapes through the partition plate 42 into tubes 72 extending above this partition plate and serving to 75

project water against the blades of the upper fan section 40.

A second cone type slinger 73 has its lower end terminating slightly above the lower end of the slinger 67. This cone at its upper end flares into substantially disk-like formation and cooperates with a superimposed baffle plate 74 to provide a restricted annular space through which water lifted by the cone or slinger 73 is projected laterally. Tie bars 75 connect the baffle 74 and the cone 73 and reference may be had to my copending application, above identified, for a detailed disclosure of the means for mounting and connecting any suitable number of slingers together.

The heavy spray thrown radially by the lower pumping cone or slinger 73 first strikes a relatively narrow and relatively fine mesh annular screen 76 which encircles the slinger closely adjacent the edge thereof, this screen being supported by hanger brackets 77 from the lower wall 38 of the volute passageway 37.

Disposed radially outwardly beyond the screen 76 is a second screen 78 considerably deeper than the first screen and preferably of slightly coarser mesh, this screen likewise being secured to the lower wall of the volute chamber. As best seen in Fig. 5, the outer screen is not completely circular but is provided with a cut-out portion at 79. This cut-out in the screen is at the side 30 of the screen remote from the side at which air enters the spray chamber so that air which has travelled around the screen to the opening can flow without further substantial resistance, inwardly and upwardly through the spray to the fan.

Preferably, baffles 79 are provided within the well 60 to prevent undue cavitation of the well water by the rapidly rotating cones or slingers.

After the volatile refrigerant is passed through the coils 22, it is led through a pipe 80 into a heat exchanger 81 disposed in the volute outlet passageway near the outlet end thereof and extending substantially across the full width of said passageway. From the heat exchanger the refrigerant gases are drawn through a pipe 81a back to the compressor 26, the refrigerant gas being sufficiently warm so that the return pipe does not frost. Unlike any other coil type exchanger with which I am familiar, the sweating exchanger 81 is contacted only by washed air and no deposit of dirt or slime can form thereon.

The cooled and humidified air leaving the volute outlet preferably passes into a duct section 90 from whence it is conveyed to any suitable point of distribution. Preferably for winter use a heating coil 91 is arranged in this duct section, it being understood that in normal summer operation no fluid passes through this heating coil and in normal winter operation the refrigerating system is idle.

Before describing the various methods of operation of this unit certain structural details are worthy of comment. In assembling the device the tank and well and valve are assembled as a unit on the support frame 20. The lower casing section 14 carrying the refrigerating coils, refrigerant connections and water connection is then placed on the frame 12, the lower end of this casing section depending into the bath in the tank. The upper casing section may then be emplaced, this section including the volute outlet conduit, the screens carried by this conduit, the air inlet filters, and the heat exchanger. This section likewise mounts the support plate 47 which carries the motor, the driv-

ing mechanism and the shaft 44 upon which the fans and slingers are mounted. The air inlet 36 with its guarding filter and with the dampers 56 may be conveniently formed in a casing section 92 (Figs. 1 and 10) bodily removable from the main upper casing section 32. The outlet duct 90 is likewise bodily removable from this upper casing section.

The brackets illustrated in Fig. 8 for supporting a refrigerating coil are merely typical of various types of brackets which may be used for this purpose. Whenever it proves desirable to do so, not only the tank but the casing sections 14 and 32 may be insulated, this being particularly desirable where the cooled, dehumidified air is to be used only at a point remote from the unit and where too great an absorption of heat from the air immediately surrounding the unit is undesirable. By having part of the refrigerating coil disposed above the water level in the tank not only is falling spray water cooled but a part of the air passing through is cooled by direct contact with a continuously washed coil which can never become dirty.

In winter operation of the device, no refrigeration is required and preferably both air inlets are open.

The lower slinger 73 drawing water from the tank projects it violently through the inner screen 76 as illustrated in Fig. 6, some of the water running down the inner side of this screen and dripping back into the tank to form an inside water curtain. The spray starts to spread fanwise between the two screens and as it passes through the outer screen 78 it expands into a still wider fan-shaped vertical cross section. The second curtain of water, of course, drips from the outer screen back into the tank. The air in order to reach the lower fan 40 must pass through the whirling fan-shaped spray exteriorly of the outer screen through one or both of the curtains of water dripping from the screen and through the still more violent or still more concentrated portion of the spray between the screens or between the slinger 73 and the inner screen. This stream of air passing through the sprays is thus very thoroughly washed and brought into very intimate contact with the spray water. The slinger 67 in tube 72 delivers smaller quantities of water into the two fans 40 and 41 and the blades of these rapidly rotating fan members finely atomize this water to create a substantially mist filled region at or just beyond the fans. Thus thorough humidification of all air passing through the fans is assured in this mist filled region and beyond the region of mist the air is whirled violently through the volute outlet conduit to centrifugally separate out any excess entrained moisture.

Fig. 4 illustrates somewhat diagrammatically the extent to which the air stream passes through the volute conduit before all excess moisture is centrifugally eliminated therefrom. Any remaining entrained solids, particularly solids which have filled the air stream in the upper fan are likewise precipitated on the wetted surface of the volute and the humidified commingled air streams pass into the duct 90, flowing in heat exchange relationship with the heater 91 and thence to their point of use. For purposes of summer cooling the dampers 56 are usually closed and the volume of air conditioned is approximately halved. In this case the rain water sprays are refrigerated so that the dew point of the air passing through these sprays is reduced and excess humidity precipitated out in the sprays. The

cold mist however, in the region of the fan insures substantially one hundred percent humidification of the cold air for any given temperature at which said air reaches the fan, although the presence of the heat exchanger in the outlet of the volute conduit may further reduce the dew point and lower the temperature of the air.

If the push rod 62 is thermostatically controlled so that it permits closing of the valve 61 when the temperature of the room has been reduced to the desired extent, substantially no further refrigeration will occur although there will still be sufficient leak of water through the valve 61 to supply the slinger 67 and thereby continue to effect humidification although very slightly cooling the air passing through the apparatus. Water will flow into the well only at a sufficient rate so that it will be all used up by the slinger 67 and there will be no water available in the slinger 73.

The violent rain water spray of course imparts a swirling motion to the water in the tank due to the angle at which it strikes the bath of water in the tank and facilitates the circulation of this water over the refrigerated coils. The use of the well prevents this swirl from being communicated to the water in the well and the use of the baffles in the well prevents undue cavitation of the well water which would prevent elevation of the necessary water to produce the rain water spray and the humidifying mist.

It will be apparent that the frame 20 may be removed and the tank 19 dropped whenever sediment is to be removed from this tank or whenever the refrigerating coil is to be cleaned. Access may be readily had to the heat exchanger 81 by removing the duct section 90.

In Fig. 5 I have illustrated somewhat diagrammatically, the manner in which the air flows substantially radially counter-current to the various sprays and the water curtain into the lower fan. The screens are of such size and of such mesh and the sprays of such violence and the curtains of the water so predetermined that they impose a substantially uniform resistance to the flow of air from the inlet toward the center of the spray chamber. As a result, part of this air flows directly through the screens and the remainder of it travels varying distances around the screen before flowing inwardly toward the center of the spray chamber. Thus, substantially all of the spray does useful work and there is no possibility of short circuiting the air directly from the inlet to the fan and consequently practically all of the air brought into intimate and relatively prolonged contact with the violent rain water sprays.

It will be seen from the foregoing description that I have provided an air conditioning unit of all year round utility and which requires but a minimum of attention.

The use of the upper fan to create a mist is of course optional and the tubes 72 may be omitted if required by the trade. Likewise it may be found desirable to eliminate either the inside or outside screen in certain types of industrial work. Where abnormal air conditions are to be maintained in certain types of plants, the air may be preheated or otherwise pretreated by any suitable means before it is taken into the machine for final treatment.

It will thus be seen that there is herein described an apparatus in which the several features of the invention are embodied and which in its action attains the various objects of the invention and is well suited to meet the requirements of practical use.

As many changes could be made in the above apparatus and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Pat- 10 ent is:

1. Air conditioning apparatus including a cas- ing having a pair of air inlets therein and a com- mon air outlet therein, a convolute chamber through which air from both of said inlets passes 15 to said outlet, a pair of fans disposed centrally of said convolute chamber, and a water spraying means disposed below said fans, one of said fans drawing air from one inlet through the spray chamber into said convolute passageway and the 20 other fan drawing air directly from the other in- let into the convolute chamber.

2. Air conditioning apparatus including a cas- ing having a pair of air inlets therein and a com- mon air outlet therein, a convolute chamber 25 through which air from both of said inlets passes to said outlet, a pair of fans disposed centrally of said convolute chamber, a water spraying means disposed below said fans, one of said fans drawing air from one inlet through the spray 30 chamber into said convolute passageway and the other fan drawing air directly from the other inlet into the convolute chamber, and means for creating a humidifying mist at the region of the fans.

3. Air conditioning apparatus including a cas- ing having a pair of air inlets therein and a com- mon air outlet therein, a convolute chamber through which air from both of said inlets passes 40 to said outlet, a pair of fans disposed one above the other centrally of said convolute chamber, and a water spraying slinger disposed below said fans, one of said fans drawing air through the spray into said convolute passageway and the other fan drawing air directly from the other in- let into the convolute chamber.

4. Air conditioning apparatus including a cas- ing having a pair of air inlets therein and a common air outlet therein, a convolute chamber through which air from both of said inlets passes 50 to said outlet, a pair of fans disposed one above the other centrally of said convolute chamber, a water spraying slinger disposed below said fans, one of said fans drawing air through the spray into said convolute passageway and the other fan drawing air directly from the other inlet into the convolute chamber, and other slinger means for projecting water into both fans to create a 55 humidifying mist at the region of the fans.

5. Air conditioning apparatus including a cas- ing having a pair of air inlets therein and a com- mon air outlet therein, a chamber through which air from both of said inlets passes to said out- let, a pair of fans discharging into said cham- ber, and a water spraying means disposed below 65 said fans, one of said fans drawing air from one inlet through the spray chamber and the other fan drawing air directly from the other inlet, said fans being of the sirocco type arranged one above the other and having a common dividing 70 plate.

6. Air conditioning apparatus including a cas- ing having a pair of air inlets therein and a com- mon air outlet therein, a chamber through which air from both of said inlets passes to said outlet, 75

5 a pair of fans discharging into said chamber, a water spraying means disposed below said fans, one of said fans drawing air from one inlet through the spray chamber and the other fan drawing air directly from the other inlet, said fans being of the sirocco type arranged one above the other and having a common dividing plate, and a second water spraying means for delivering relatively minute quantities of water to 10 the interior of the fans to be broken up as a humidifying mist by the fans.

10 7. In an air conditioning apparatus, a casing including two sections mounted one upon the other, a tank into which the edge of the lower casing extends, means carried by said lower casing section for supplying water to the tank, said upper casing section having an air inlet therein and an air outlet therein and means mounted on said upper casing section for elevating water 15 from the tank and spraying it into the air stream passing through the casing, a refrigerating coil for the tank water carried by said lower casing section.

20 8. In an air conditioning apparatus, a casing including two sections mounted one upon the other, a tank into which the edge of the lower casing extends, means carried by said lower casing section for supplying water to the tank, said upper casing section having an air inlet therein 25 and an air outlet therein and means mounted on said upper casing section for elevating water from the tank and spraying it into the air stream passing through the casing, a refrigerating coil for the tank water carried by said lower casing 30 section, a fan disposed in the upper casing section and a super-cooler arranged between the fan and the outlet and through which refrigerant flows after leaving the cooling coil for the tank.

35 9. In an air conditioning apparatus, a casing and a water tank arranged at the lower end of said casing, a shaft pendant from the top of said casing, water elevating and spraying means carried by the shaft, a pair of fans carried by the shaft, a volute outlet passageway into which air is blown by the fans, a pair of inlet passageways, 40 one of which communicates directly with one of the fans and the other of which communicates

45 with the other fan through the spray chamber and means for elevating relatively minute quantities of water and delivering it into the fans.

10 10. In an air conditioning apparatus, a casing and a bath of refrigerated water at the lower end thereof, a mounting plate closing an opening in the top of the casing, a rotatable shaft pendant from said plate, a fan carried by the shaft, a slinger also carried by said shaft and dipping into the water and adapted to spray water, an air 10 inlet in said casing from which air is drawn through the sprays by the fan, a volute outlet in said casing into which air is blown by the fan, the lower portion of said volute outlet carrying a pair of concentrically disposed screens through 15 which water from the slinger is thrown into the path of the air stream.

11. In an air conditioning apparatus, a casing and a bath of refrigerated water at the lower end thereof, a mounting plate closing an opening 20 in the top of the casing, a rotatable shaft pendant from said plate, a fan carried by the shaft, a slinger also carried by said shaft and dipping into the water, an air inlet in said casing from which air is drawn through the sprays by the fan, 25 a volute outlet in said casing into which air is blown by the fan, the lower portion of said volute outlet carrying a pair of concentrically disposed screens through which water from the slinger is thrust into the path of the air, the inner screen 30 being disposed close to the periphery of the slinger and of finer mesh than the outer screen.

12. In an air conditioning apparatus, a casing and a bath of refrigerated water at the lower end thereof, a mounting plate closing an opening 35 in the top of the casing, a rotatable shaft pendant from said plate, a fan carried by the shaft, a slinger also carried by said shaft and dipping into the water, an air inlet in said casing from which air is drawn through the sprays by 40 the fan, a volute outlet in said casing into which air is blown by the fan, a refrigerating coil for cooling the spray water and a heat exchanger in series with said coil and disposed in the volute outlet passageway and through which refrigerant 45 from the water cooling coil flows, whereby to super-cool the air leaving the volute.

EDWARD S. LEA.
